UNITED STATES PATENT OFFICE.

ROBERT E. GOSNEY, OF BISHOP, CALIFORNIA, ASSIGNOR OF ONE-HALF TO HENRY C. TRAVER, OF BISHOP, CALIFORNIA.

QUICK-CHANGING NEEDLE-PLATE HOLDER.

Application filed July 18, 1921. Serial No. 485,494.

To all whom it may concern:

Be it known that I, ROBERT E. GOSNEY, a citizen of the United States, residing at Bishop, in the county of Inyo and State of California, have invented new and useful Improvements in Quick-Changing Needle-Plate Holders, of which the following is a specification.

As in my U. S. Patent No. 1,375,383, my present invention is an improvement in attachments for shoe stitching machines, in the nature of a needle plate holder which permits the changes to be made from a leather or knife needle plate to a rubber or lip needle plate as may be required without the detachment of screws or the like, and has for its object to improve the construction of my said patent.

In the drawings which accompany and form part of this specification:—

Figure 1 is a perspective view of the attachment.

Figure 2 is an approximately central vertical longitudinal sectional view through the same.

Figure 3 is a perspective view of the combined gauge and needle plate securing member, looking toward the under face thereof.

Figure 4 is a top plan view of the needle lip plate, the knife needle plate being shown in Figures 1 and 2.

While my present improvement has reference only to the combined gauge and needle plate securing member, I have, in the accompanying drawing, illustrated the same in applied position upon the cap, and therefore I will, in the following description make brief reference to the cap construction and the needle lip and knife needle plates.

The cap is indicated by the numeral 5 and has secured on its under face, at its front end a plate 6 that is provided with threaded openings which register with similar openings in the flat top of the cap. Through these openings pass the threaded shanks of screws whose kerfed heads are received in spaced openings in the knife needle plate 6, as well as in similar openings in the lip needle plate 7, when the same is attached to the cap.

The top of the plate 5 to the rear, but in a line with the bolts which secure the plates to the cap has an opening therethrough, and through this opening passes a bolt member 8. The head of the bolt is in contact with

the under face of the top of the cap 5, and its threaded shank is engaged by a binding nut 9 that rests on the top of the cap. The nut 9 is received in a longitudinal groove 11 on the under face of a metallic bar 12, 60 the said bar being provided with an elongated slot 13 of a length equalling that of the groove, but of a width less than that of the groove, the width of the slot being approximately equal to the cross sectional diameter of the bolt 8, while that of the slot being equal to the cross sectional diameter of the nut 9. Thus, both the nut and the bolt provide guide members for the bar 12. The bar 12, on its flat under face and at its 70 forward end is formed with a recess 14, the latter entering from its outer end and from one of its sides and communicating with the groove. The recess terminates in a straight wall 15 at one of the sides of the bar 12. The 75 recess 14 receives therein the plate 6 or the plate 7, and the shoulder provided by the wall 15 is in contacting engagement with one of the edges of either of the said plates 6 or 7. The bar 12, at its forward end is 80 rounded, as at 16, the said end being reduced and the rounded sides thereof extending to the sides proper of the bar. Also the forward end of the bar is of a materially greater thickness than the remainder of the said bar, 85 the upper face of the bar gradually decreasing in thickness from its said forward end to its rear end, the last mentioned end being substantially feathered.

The bolt 8 is engaged by a winged nut 17 90 which is designed to exert a frictional contact with the upper bar of the bar 12. The improvement provides an effective housing for the plate 6 or 7, the wall or shoulder 95 15 assisting the heads of the screws, which, for distinction, are indicated by the numeral 18 in preventing a side movement of the said plates on the cap, while the elongated slot through which the bolt 8 passes permits of the guide end of the bar 12 being 100 properly adjusted with respect to the needle openings in the plates 6 and 7. The front thickened and rounded end of the bar provides a leather guide, as will be apparent to those skilled in the art to which the invention appertains, and with my improvement the plate 6 or 7 may be quickly attached or removed from the cap of the stitching machine without the requirement 105 of tools and without the removal of the 110

screws 18, it being understood that only the heads of the said screws are received in the openings in the said plates, or in other words that no binding action between 5 the screws and plates occur, so that when the bar is moved off of either of the plates, the latter may be lifted from the cap.

Having described the invention, I claim:—

- 10 1. The combination with a cap of a stitching machine having headed members adjacent to one end thereof and a plate provided with openings which receive the heads of the said members therein, of a bar longitudinally adjustable on the cap and having one of its ends recessed to receive therein the rear portion of the plate, and said recess having a side wall which is in contacting engagement with one of the edges of 20 the said plate.
2. The combination with the cap of a stitching machine having spaced headed elements adjacent one end thereof, a bolt in a line with or to the rear of said headed elements, a nut screwed on the bolt and in contacting engagement with the top of the plate, of a bar having its under-face grooved longitudinally to receive therein and to have the opposite walls provided thereby 25 contacted by the sides of the nut, said bar having an elongated slot of a width approximately equalling the cross sectional diameter of the bolt receiving the latter therein, a winged nut screwed on the bolt and 30 contacting the bar, a needle plate having 35

openings freely receiving therein the headed elements, and said bar having its forward end provided with a recess forming a pocket for the reception of the rear portion of the needle plate.

3. The combination with the cap of a stitching machine having aligning headed elements adjacent to one end thereof, a threaded element to the rear but in a line with the headed elements, a nut on the 45 threaded element, a winged nut also on the threaded element and a needle plate having openings to freely receive therein the headed elements, of a combined holder for the plate and a leather guide, comprising a bar 50 having its under face flat but formed with a central groove to receive therein the nut and having an elongated slot communicating with the groove to receive therethrough the threaded element and the outer face of 55 the said bar designed to be frictionally contacted by the winged nut on the threaded element, said bar having its under face at its front end recessed to provide a pocket which receives therein the rear portion of 60 the plate and which also provides a wall that is in contacting engagement with one of the edges of the plate, said front end of the bar being of a greater thickness than the remainder of the said bar and being reduced and rounded and flared to the sides 65 of the bar, as and for the purpose set forth.

In testimony whereof I affix my signature.

ROBERT E. GOSNEY.
